UNITED STATES PATENT OFFICE.

STACY B. HASELTINE, OF CHICAGO, ILLINOIS, ASSIGNOR TO WILLIAM H. MINER, OF CHAZY, NEW YORK.

DRAFT-GEAR YOKE.

1,242,799.

Specification of Letters Patent.

Patented Oct. 9, 1917.

Original application filed September 13, 1912, Serial No. 720,153. Divided and this application filed September 8, 1914, Serial No. 860,533. Renewed August 27, 1917. Serial No. 188,483.

To all whom it may concern:

Be it known that I, STACY B. HASELTINE, a citizen of the United States, residing in Chicago, in the county of Cook and State of Illinois, have invented a certain new and useful Improvement in Draft-Gear Yokes, of which the following is a full, clear, concise, and exact description, reference being had to the accompanying drawings, forming a part of this specification.

My invention relates to improvements in draft gear yokes.

The object of my invention is to provide a simple and efficient means of connecting the draw-bar and draft yoke in railway draft rigging, and one in which the draw-bar and draft yoke may be easily connected and disconnected.

In the accompanying drawings forming a part of this specification, Figure 1 is a side elevation of the forward end of a draft yoke and the rear end of a draw-bar embodying my invention; Fig. 2 is a view partly in plan and partly in horizontal section on line 2—2 of Fig. 1; Fig. 3 is a vertical sectional view on line 3—3 of Fig. 2; Fig. 4 is a transverse sectional view on line 4—4 of Fig. 1; and Fig. 5 is a detail perspective view of the block employed with my improvement.

In said drawing, the draw-bar shank 32 and the butt thereof 33 are shown as provided with the usual upper and lower transverse shoulders 34 and 35 respectively; the draft yoke 36, the forward end of which is shown in the drawing, has an upper strap 37 and a lower strap 38; the upper strap 37 being provided with a downwardly turned gib 53, engaging the upper shoulder 34 of the draw-bar. The lower strap 38 is provided with the downward turn or bend 39, in front of which it is forwardly extended in a plane parallel with the opposite portion of the upper strap and a sufficient distance therefrom to permit the butt of the draw-bar to clear the gib 38 in inserting the draw-bar through the forward opening of the yoke. The upper and lower straps of the yoke are forwardly joined by the lateral webs or plates 40, 40, thus providing a head for the yoke with a box-like opening 41, into which the draw-bar is received. The webs 40, 40, are transversely provided near their lower edges with the slot 42 to receive the transverse key 43, which passes therethrough

and through the transverse perforation 44 in 55 the L-shaped block 45. The block 45 has an upright member 46 and a flat member 47, forming the shoulder 48, against which the lower shoulder 35 of the butt of the draw-bar engages in normal position with the 60 draft rigging. The top face 49 of the member 47 of the block 45, when in position, is substantially even with the inner portion or upper face 50 of the lower yoke strap 38, back of the bend 39 therein. The key 43 is 65 provided with the perforations 51, 51 at its ends to receive the cotters or pins 52, 52.

The operation of my device will be clear. To remove the draw-bar, the block is withdrawn, permitting the butt of the draw-bar 70 to be moved downwardly so that the upper shoulder thereof may clear the gib of the upper yoke strap and be forwardly withdrawn. To connect the draw-bar with the yoke, the butt of the draw-bar is inserted in 75 the box-like opening of the member of the yoke, lifted to position so that the upper shoulder of the draw-bar engages the gib in the upper strap of the yoke and then the block is inserted in the lower portion of the 80 said opening so that the shoulder thereon engages the lower shoulder of the draw-bar and the block is then secured in position by passing the key therethrough. It will be seen that on the rearward movement of the 85 draw-bar, the butt of the same will engage directly with the followers or compression resisting members within the yoke and without strain upon the yoke, while on the forward movement of the draw-bar the shoulders of the same will be in engagement with the shoulders provided on the upper strap 90 of the yoke and upon the block.

This application is a division of my co-pending application No. 720,153, filed Sep- 95 tember 13, 1912, for improvement in means of connecting draw-bar to draft yoke in railway draft rigging.

I claim:

1. In a device of the class described, a 100 draw-bar provided with oppositely disposed shoulders, a yoke forwardly provided with a laterally slotted, hollow box-like head to receive the draw-bar, a transverse shoulder within said yoke adapted to engage one 105 shoulder of the draw-bar, a removable block provided with a shoulder adapted to engage the other shoulder of said draw-bar and a

key adapted to secure said removable block within the said head.

2. The combination, with a yoke having top and bottom members, the top member having a coupler engaging gib, and aper-tured side plates uniting the forward ends of the top and bottom members, of an aper-tured locking block adapted to fit between the side plates and having a coupler engag-ing gib, and a key for passing through the apertures of the side plates and the locking block.

3. A coupler yoke comprised of two for-wardly extending arms adapted to receive 15 between them a coupler liner block, a filler block located between the coupler liner block and the lower yoke arm, said filler block having a recess in its lower side adapted for reception of a key for securing 20 the filler block to the yoke.

4. A yoke having longitudinally extend-ing arms connected by side walls at their forward ends to form a housing, opposite abutments within said housing, one of said 25 abutments being formed on a longitudinally removable member, and a laterally removable key, for securing said removable mem-ber within the housing.

5. A coupler yoke comprised of longitu-dinally extending arms connected together 30 at their forward ends to form a housing, a coupler butt inserted in said housing and having a pulling engagement with a wall thereof, a longitudinally removable filler

block seated on the opposite wall and hav-ing a pulling engagement with the coupler butt, and securing means for said filler block removable laterally and in a plane en-tirely below the under side of said coupler butt.

6. As an article of manufacture, a yoke for draft riggings, said yoke having a hollow box-like head at the forward end thereof within which is adapted to be received a draw bar butt, the upper wall of said head being provided with a shoulder adapted for engagement with the upper shoulder of a draw bar butt under draft, the distance between the lower wall of said head and said shoulder on the upper wall thereof be-ing sufficient to permit the insertion of the draw bar butt by longitudinal movement relatively to the yoke, a shouldered locking block arranged to extend under the lower surface of the draw bar butt and to engage 55 the front face of the lower shoulder thereof, said block, when in position, supporting the draw bar butt with the upper shoulder thereof in alinement with the shoulder of said head, and a removable key extending through slots provided in the yoke head and in said block for retaining the latter in operative position.

STACY B. HASELTINE.
